UNITED STATES PATENT OFFICE.

CHESTER F. GERNERT, OF READING, PENNSYLVANIA, ASSIGNOR TO READING CHAIN BLOCK CORPORATION, OF READING, PENNSYLVANIA, A CORPORATION OF PENNSYLVANIA.

HOIST-CABLE GUIDE.

Application filed January 14, 1924. Serial No. 685,979.

To all whom it may concern:

Be it known that I, CHESTER F. GERNERT, a citizen of the United States, residing at Reading, in the county of Berks and State 5 of Pennsylvania, have invented certain new and useful Improvements in Hoist-Cable Guides, of which the following is a specification.

This invention relates to improvements in 10 cable guides, and the object in the present instance is to provide a guide for a hoist cable that will serve to keep the cable in line as it approaches the drum to be wound thereon.

15 The particular feature of the present invention is to provide a guide that may be placed in position without removing the cable from the drum or other portion of the mechanism, and I accomplish this by making the guide in two parts, one of which consists of a loop member capable of being easily and rapidly removed from the body portion, and which may be slipped over the cable and then secured in position again, 20 with the cable passing through the loop and in proper alignment for winding.

25 The invention is more fully described in the following specification and clearly illustrated in the accompanying drawing, in which:—

Figure 1 is a side elevation of the guide. Figure 2 is a front elevation thereof.

Figure 3 is a plan view thereof.

Figure 4 shows the guide loop in detail.

30 The numeral 1 designates the body of the guide, which comprises a metal plate having its upper end bent at an angle to provide means for securing it in position.

35 The lower extremity of the body is formed with a centrally disposed lug 3, formed by bending a portion of the body out of the vertical line, preferably with a die.

40 The numeral 5 designates the cable loop, through which the cable passes and which 45 acts as a guide therefor.

This loop member is made of metal and

bent to the form of an approximate oval, but with a space left open between the ends thereof, as indicated at 6. This loop portion is tapped to receive bolts 7 by means of 50 which it may be attached to the lower extremity of the body 1, and the space 6 is slightly greater than the width of the lug 3, and when the loop is in position, as indicated, this lug will occupy the space between 55 the ends of the loop, thus completing the inner line of the loop and preventing the cable from entering the space 6.

In use, the loop is placed about the cable, while the cable is suspended from the hoist 60 drum, and then attached to the body portion of the guide 1 by means of a pair of bolts 7.

Any slight adjustment that may be desired in the vertical alignment of the cable, may be secured by tilting the body member 1 on its 65 supporting angled end 2.

It will be noted that the guide loop may be made of different sizes, to accommodate different size cables, and that it will not be necessary to remove the guide proper, but 70 merely to remove the loop portion and replace it with one of the desired size.

Having thus described my invention, I claim:—

1. A guide for hoist cables comprising a 75 vertical body having an angled upper end and a lug formed on its lower end and centrally disposed, in combination with a removable loop member formed with an open space to accommodate the lug, and means 80 for securing the loop member to the body.

2. In a cable guide, a flat metal body having its upper end bent at an angle thereto and formed with a centrally disposed lug at its lower extremity; a guide loop of substantially 85 oval contour and having an open space in one portion thereof adapted to accommodate said lug, and means for securing the loop member to the body member.

In testimony whereof I affix my signature.

CHESTER F. GERNERT,
